Inventor.

UNITED STATES PATENT OFFICE.

WILLIAM H. HAAS, OF DETROIT, MICHIGAN, ASSIGNOR TO MURPHY IRON WORKS, OF DETROIT, MICHIGAN, A CORPORATION OF MICHIGAN.

STOKER.

1,273,481.

Specification of Letters Patent.

Patented July 23, 1918.

Application filed November 11, 1914. Serial No. 871,484.

To all whom it may concern:

Be it known that I, WILLIAM H. HAAS, a citizen of the United States, residing at Detroit, in the county of Wayne and State 5 of Michigan, have invented certain new and useful Improvements in Stokers, of which the following is a specification.

The leading object and salient feature of the present invention is the production of a 10 stoker mechanism for underfeed furnaces which shall be simple in structure, economical to manufacture, easy to repair and operate, and in which the fuel feed may be readily modified to meet the required needs 15 of the service and the character of the fuel employed. Fuel retorts in this style of furnace with reciprocable bottom walls or floors have been heretofore proposed, but none of these have been equipped with coal 20 pushers movable with the retort-bottom and adjustable to vary or regulate the feed or advancement of the fuel. Much less have such retort bottoms or walls been provided with independently adjustable fuel pushers, 25 so that the feed of fuel in the different portions of the furnace may be controlled effectively. It is to improvements along these lines that the present invention is directed.

A desirable embodiment of this invention 30 has been illustrated in the accompanying drawing forming a part of this specification, and to which reference should be had in connection with the following detailed description. Throughout the various views of this 35 drawing, like reference characters refer to the same parts.

In the drawing,—

Figure 1 is a longitudinal section through the furnace construction, with certain parts 40 broken away to more clearly illustrate the structure;

Fig. 2 is a plan view of the retort, its fuel 45 pushers and their adjusting devices, the grate bars and other parts being omitted for clearness of illustration; and

Fig. 3 is a fragmentary vertical cross-section on line 3—3 of Fig. 1, the parts being viewed in the direction indicated by the arrows.

50 In this preferred embodiment of the invention, there are provided for the retort two side plates or supports 10 and 11 (Figs. 1 and 3), each having on its inner surface a horizontal rib or ledge 12, 12. The retort bottom wall or floor 13, and the lower por-

tions 14, 14 of the retort side-walls, are desirably cast in one piece and provided with outstanding ribs 15, 15 at their upper edges; resting and slidable on the supporting ribs 12, 12, the floor or bottom wall having at 60 certain points one or more substantially semicylindrical cavities or recesses 16 and 17, two in the present instance, although the exact number is not important. The upper portions 18, 18 of the retort side-walls are 65 disposed above the parts 14, 14 and bolted at 19, 19 to the supports 10 and 11 so that their inner faces will be substantially flush with the corresponding faces of the parts 14, 14. The grate bars 20, 20, which may be 70 of any suitable design or form, rest upon the tops of the supports 10 and 11, and incline downwardly from the retort on opposite sides thereof. The parts 13 and 14 may, if preferred, be cast in sections and bolted 75 together at 21, 22, and, in order to strengthen these castings, they may be equipped with depending marginal stiffening ribs 23, 23.

The front wall of the furnace is illustrated at 24, and the bridge wall at 25, the retort 80 at the bridge wall having a downwardly-curved rear wall 26 which facilitates or occasions the upward passage or forcing of the coal as it is pushed rearwardly by the coal pushers. The front of the furnace is 85 provided with a hopper 27 which delivers the fuel into a chamber 28 in front of the furnace and in communication with the retort. The coal which enters the chamber 28 is forced rearwardly into the retort by 90 means of a plunger 29 fixed to the reciprocating retort-bottom.

Any suitable mechanism may be employed for sliding the retort bottom and the pushers which it carries. In the present instance 95 I have illustrated a shaft 30 carrying a disk 31 connected to the retort floor by means of a pitman or link 32, whereby the slow rotation of the shaft 30 will cause the pitman to travel inwardly and outwardly, thereby 100 bringing about proper reciprocation of the movable parts of the retort; it being understood that the shaft 30 is rotated relatively slowly by any proper mechanism, not illustrated.

To supplement the action of the piston or plunger 29 and to bring about an even desirable distribution of the coal in the retort and on the inclined grates, I provide each of the cavities 16 and 17 with a substantially 105

semicylindrical coal or fuel pusher 33 and 34, respectively. The pusher 33 is fixed and mounted on a transverse shaft 35 supported in the sides of the sliding portion of the 5 retort and projecting through the farther side, as illustrated. The other pusher 34 is similarly mounted on the shaft 36 accommodated in bearings in the slidable side walls of the retort and projecting beyond the near 10 side wall, as shown in Figs. 1 and 2, the projecting part having a gear sector 37, the teeth of which are in mesh with those of a rack 38 carried on the end of a bar 39 slideable in the supports or bearings 40 and 41. 15 The front end of the bar 39, by means of a pin and slot connection 42, is connected to an adjusting handle 43 fulcrumed at 44 and carrying a locking dog 45 adapted to take into any one of a plurality of apertures 46 20 on an arcuate flange forming a part of a member 48 suitably supported on the sliding portion of the retort, so that as the floor or bottom wall 13 and the portions of the retort side-walls rigid therewith slide back 25 and forth, not only the fuel pushers 33 and 34 will be carried by it, but also each of their adjusting mechanisms. It is to be understood that the shaft 35 of the coal pusher 33 is adjusted by a mechanism like 30 that described for the shaft 36, but which is located at the other side of the retort, and comprises a gear sector 49, rack 50, reciprocating bar 51, bearings 52, 52, adjusting handle 53, locking dog 54, and notched, 35 apertured flange 55. It should be noted that the top face of each of the fuel pushers 33 and 34 is substantially, though not exactly, flat and inclined at a slight elevation. It should be observed also that when these 40 pushers are in the positions illustrated in Fig. 1, a portion of their rear abrupt walls is exposed, and a portion of the abrupt front walls of the cavities 16 and 17 is likewise exposed to the fuel. The result is that when 45 the retort floor travels forwardly, these pushers, owing to the slight inclination of their top faces, readily ride under the fuel without materially disturbing it; but when the retort floor and the pushers are caused 50 to travel rearwardly, the abrupt exposed faces of the pushers and recesses engage the fuel and push it rearwardly and upwardly, so that the coal is fed not only rearwardly, but also upwardly, so as to overflow onto 55 the oppositely inclined grates.

In some cases it may be desirable, due to the kind of service required or the character of the coal employed, to vary the feed, and this can be accomplished by manipulation 60 of either or both of the handles 43 and 53, so as to modify the extent of the projection of the pushers into the retort and the extent of exposure of the recesses to the fuel. Obviously, the more the pushers are rocked to 65 project into the retort, the greater the fuel

feed, and the less they project into the retort the smaller the coal feed.

It should be clear that by manipulating either of the handles 43 or 53, the corresponding pusher can be angularly adjusted 70 and held in such new position by the locking of the handle with its corresponding apertured flange, which of course is concentric with the fulcrum of the handle. In the present instance, the locks 45 and 54 are 75 nothing more than manually removable pins which act to lock the levers to their flanges, but of course other devices performing the same or equivalent function might be employed with equally good results. 80

The claims of this application are not to be limited and restricted to the details of construction shown and described, because in this application I have merely attempted to show a desirable embodiment of the invention, it being understood that the latter is susceptible of many embodiments varying more or less in mechanical structure, but all incorporating the features of advantage accruing from the employment of the invention. 90

I claim:

1. In an underfeed-furnace stoker construction, the combination of a fuel-retort having a recessed slidable wall, means to reciprocate said wall, a fuel-pusher accommodated in said recess and adapted to travel with said wall and remain fixed in position relative thereto during the movements of the wall, and means to adjust the position of said 95 pusher in said recess to vary the extent of exposure of the wall of the recess to the fuel whereby to regulate the fuel feed without modifying the action of said wall-reciprocating means, substantially as described. 100

2. In an underfeed-furnace stoker construction, the combination of a fuel-retort having a recessed slidable wall, means to reciprocate said wall, a fuel-pusher adjustably accommodated in said recess, adapted 110 to travel with said wall and remain fixed in position relative thereto during the movements of the wall, and constructed so that adjustment thereof will vary the extent of the projection of the pusher into the retort 115 and will modify the extent of exposure of the recess wall to the fuel, whereby to regulate the fuel feed, and means to adjust said fuel-pusher without modifying the action of said wall-reciprocating means, substantially 120 as described.

3. In an underfeed-furnace stoker construction, the combination of a fuel-retort having a slidable wall, means to reciprocate 125 said wall, a plurality of fuel-pushers carried by said wall and adapted to travel with the wall and remain fixed in position relative thereto during the movements of the wall, and means to adjust said pushers independently to regulate the fuel-feed without modi- 130

fying the action of said wall-reciprocating means, substantially as described.

4. In an underfeed-furnace stoker construction, the combination of a fuel-retort having a slidable floor provided with a plurality of recesses, means to reciprocate said floor, a fuel-pusher in each of said floor recesses disposed transversely of the direction of the movements of the floor and adapted to remain fixed in position relative to the floor during the movements of the latter, and means to turn said pushers independently about their axes to adjust their positions to regulate the fuel feed, without modifying the action of said floor-reciprocating means, substantially as described.

5. In an underfeed-furnace stoker-construction, the combination of a fuel-retort having a slidable floor with a substantially semi-cylindrical transverse cavity, a substantially semi-cylindrical fuel-pusher accommodated in the cavity and adapted to project into the retort, and means to turn said pusher about its axis to adjust its position, whereby to regulate the fuel-feed, substantially as described.

6. In an underfeed-furnace stoker-construction, the combination of a fuel-retort

having a slidable floor equipped with a plurality of substantially semi-cylindrical transverse cavities, means to reciprocate said floor, a substantially semi-cylindrical pusher accomodated in each of said cavities and adapted to project varying amounts into the retort, and means to rock said pushers about their axes to adjust their positions, whereby to regulate the fuel feed, substantially as described.

7. In an underfeed-furnace stoker-construction, the combination of a fuel-retort having a floor and portions of its side-walls slidable, said floor having a transverse-cavity, a shaft extended through one of said movable side-wall portions, a fuel-pusher in said cavity mounted on said shaft, a handle fulcrumed on the movable portion of the fuel-retort, and means connecting said handle and projecting part of the shaft, whereby the shaft may be angularly adjusted to regulate the position of the pusher and govern the fuel feed, substantially as described.
